UNITED STATES PATENT OFFICE.

RUFUS A. FREEMAN, OF FLUSHING, NEW YORK.

METHOD OF MAKING ARTICLES FROM SHEET-RUBBER.

1,340,882.

Specification of Letters Patent. Patented May 25, 1920.

Application filed May 17, 1917. Serial No. 169,385.

To all whom it may concern:
Be it known that I, RUFUS A. FREEMAN, a citizen of the United States, residing at Flushing, in the county of Queens and State 5 of New York, have invented certain new and useful Improvements in Methods of Making Articles from Sheet-Rubber, of which the following is a specification, reference being had therein to the accompanying 10 drawing.

This invention relates to the manufacture of articles from sheet-rubber and has reference more particularly to the formation of such articles as dress shields, rubber 15 caps and the like, in which complementary blanks are united along a portion of their edges. In the case of a dress shield two blanks constituting the flaps of the shield are united along their upper edges, while in 20 the case of a bathing cap two complementary blanks of general semicircular form are united along the curved edges and are left free at their straight edges.

It is a quality of unvulcanized thin sheet- 25 rubber that if two sheets be placed together face to face and subjected to the action of a dull cutting or severing edge or die, the material will be severed along said edge, but in the severing action the material of the 30 sheets will unite along the severed edges, and an integral connecting joint will be formed somewhat similar in its characteristics and structure to a welded joint. If however the cutting edge is sharp, the material of the sheets will be incised without 35 becoming united.

My invention is based on this peculiar 40 action of the material of the sheets in uniting along the severed edges, and the invention comprehends an improved method of 45 forming articles from separate sheets of unvulcanized rubber, which method will be fully described in the specification to follow and the novel characteristics of which will be set forth in the appended claims.

In the accompanying drawings I have 50 illustrated two forms of apparatus for carrying my improved method into effect, but it will be manifest, however, that my improved 55 method is not restricted in its practice to apparatuses of the form shown, and may be carried into effect by other means.

In the accompanying drawings:

Figure 1 is a sectional elevation of one 55 form of apparatus employed for carrying my improved method into practice.

Fig. 2 is a face view of the incising and severing die.

Fig. 3 is a sectional elevation, on an enlarged scale on the line *a—a* of Fig. 2. 60

Fig. 4 is a sectional elevation of an apparatus of different form.

Figs. 5, 6 and 7 are face views respectively of the two incising dies and the severing die of the apparatus shown in Fig. 4. 65

Fig. 8 is a plan view of portions of superposed strips of sheet rubber showing at the upper part of the figure, the blanks incised along the sides and bottoms of the flaps of a dress shield, and showing at the lower part 70 of the figure the upper edges of the blanks severed from the strips and united together.

Fig. 9 is a perspective view of the completed dress shield.

Fig. 10 is a plan view of portions of superposed strips of sheet rubber showing complementary semicircular blanks severed therefrom and united along the severed edges to produce bathing caps. 75

Fig. 11 is a sectional perspective view of 80 one of the bathing caps taken on the line *b—b* of Fig. 10.

Fig. 12 is a face view of the die for forming bathing caps shown in Figs. 10 and 11.

Referring to the drawings:

In carrying my improved method into practice in its most simple procedure, and for instance for the production of dress shields, I provide two strips of thin unvulcanized sheet rubber and place them flatly 90 face to face or superpose them one upon the other, and I give the superposed sheets a suitable support so that they may be acted on in accordance with my invention. The sheets thus superposed and supported are 95 then acted on by a suitable die provided with a curved sharp cutting edge conforming to the contour of the sides and bottoms of the flaps of the dress shield, and provided also with a comparatively dull severing edge 100 conforming to the curved upper edges of the two flaps. The die thus formed being forcibly pressed against the superposed sheets, the latter will be incised along the lines of the sharp cutting edge with the result that 105 blanks will be separated from the sheets and forming the two flaps of the dress shield with their side and bottom edges disconnected from each other. Simultaneously the material of the sheets will be severed along 110 the line of the dull severing edge of the die, thereby separating the blanks from the strip.

along a line corresponding to the upper edges of the flaps and at the same time causing these edges to unite with each other and effecting an integral connection of the two flaps along their upper edges.

- In the foregoing operation the incising and severing dies act at one time on the superposed sheets. This simultaneous action however is not essential to the practice of my invention, as the two sheets may be acted on separately by incising dies to form the sides and bottoms of the flaps, the two sheets then brought together and superposed one upon the other with the incisions in register with each other, and finally the severing and uniting action performed to completely separate the blanks from the sheets and cause the upper edges of the flaps to become united.
- In the formation of bathing caps, the sheets are superposed as in the first described procedure, and subjected to a single die with a dull cutting edge of general semicircular contour and so disposed that the edge will intersect the straight edges of the sheets at one side. The operation of such a die will result in the complete severance of complementary semicircular blanks from the sheets, with their curved edges united and joined and their straight edges disconnected from each other and producing a bathing cap.

In Fig. 1 of the drawings a form of mechanism is shown by which my improved method may be carried into effect in the manner first described for the production of dress shields. Referring to this figure it will be seen that there is provided a horizontal fixed flat bed 1 preferably of steel, above which is arranged a vertically reciprocating head 2 provided on its lower face with a sharp incising die or cutting edge 3 of a contour corresponding to the sides and bottoms of the flap of a dress shield, and provided also with a comparatively dull edge or severing die 4 which corresponds to the upper curved edge of the flaps of the dress shield and which connects at its ends with the ends of the cutting edge 3. The cutting die 3 is beveled on opposite sides to produce a sharp cutting edge as shown in Fig. 3, while the severing die 4 is straight on one side as at 4^a, is beveled on the opposite side as at 4^b, and has its extreme edge flat or dull as at 4^c, the purpose of which peculiar formation of the die will presently appear.

5 and 6 indicate rolls of unvulcanized thin sheet rubber wound on rotary spools 5^a and 6^a mounted one in advance of the other at one side of the reciprocating head 2, the sheets from these rolls being led around guide bars 5^b and 6^b respectively, arranged adjacent the bed 1; and from these guide bars the sheets pass beneath the die head 2 and

over the bed 1, being superposed one upon the other and supported by the bed. Beyond the bed the sheets pass between upper and lower feed rollers 7 and 8, which being rotated by suitable means in the direction of the arrows thereon, will serve to draw the sheets of material horizontally in superposed condition over the bed.

With the strips thus superposed and supported by the bed, when the head 2 is lowered and the dies thereon pressed with considerable force upon the sheets, the sharp edge of the cutting die 3 will incise the material along the curved line of the cutting edge, thereby forming the side and bottom edges of the flaps 9 of the dress shield, which edges will be free and separated from each other. Simultaneously with this action, the blunt severing die 4 will act on the material in a curved line along the upper edges of the flaps and will, owing to the form of the active edge of the die, sever the incised portions from the sheets and at the same time will compress or compact the severed edges together as shown in Fig. 3, to the left, thereby causing these edges to unite with each other in the form of an integral or welded joint. In this action of the die 4 the straight edge 4^a will serve to sever the material at that side, while the beveled edge 4^b will act as a pressure surface and will mash or impact the severed edges of the blanks together.

The result of this operation is the production by the single action of the die head, of a complete dress shield consisting of the two usual side flaps united integrally at their upper edges as shown in Fig. 9.

In the operation of the mechanism described, the material is fed by the feed rolls 7 and 8, between each action of the die head, the sheets being advanced when the die head rises, and remaining at rest when the die head descends to perform the incising and severing actions. By reason of the unvulcanized state or condition of the rubber sheets, they are liable to permanent deformation or distortion if subjected to undue strain or tension, and therefore it is necessary that in the feed of the sheets beneath the die, they be entirely free from strain or pull. To provide for this condition the sheets at a point between the supply rolls and the guide bars are given slack and hang loose as shown at 5^c and 6^c (Fig. 1), and suitable means are provided for rotating the rolls of material so as to unwind the material therefrom. The feed rolls 7 and 8 are timed with relation to the rotation of the rolls 5 and 6 so that the surface speed of the feed rolls and the rolls 5 and 6 will be the same. In this way the feed rolls will act to draw over the bed, merely loose lengths of the material, and the slack being in this way maintained, the sheets are never

subjected to a pull or strain which would be liable to deform the material or draw it out of shape, while at the same time the two sheets are advanced in superposed condition over the bed and beneath the die.

In the foregoing description it will be seen that the effect of the operation of the mechanism with the incising die and severing die acting on the superposed sheets, is to 10 incise two sheets and form two blanks, which blanks are severed from the sheets along a line intersecting the incisions and are united along the severing line, thus producing a dress shield.

15 The mechanism so far described is employed for making dress shields in accordance with my improved method, but it is applicable as well to the formation of bathing caps of the form shown in Fig. 10. The 20 only change required would be in the form of the die which, instead of consisting of a sharp cutting edge 3 and a dull severing edge 4, would be made up of a single dull severing edge only, of the form shown in 25 Fig. 12, so as to sever from the two sheets complementary blanks of the form shown in Fig. 10. The superposed sheets being drawn over the bed as before, and the head being furnished with a severing die of the 30 form shown in Fig. 12, the material of the sheets will be acted on by the severing edge which will sever and separate therefrom semicircular blanks, and at the same time will unite the curved severed edges of the 35 blanks throughout their extent, as shown in Fig. 11. The die is so related to the edges of the sheets at one side that the die will intersect said edges, with the result that the straight edges of the blanks will be left free 40 and disconnected, but the curved edges will be connected throughout their extent.

In Figs. 4, 5, 6 and 7 I have represented a different form of apparatus for practising my method. In this case instead of incising 45 both sheets at one operation while the sheets are superposed as in the first instance described, they are incised separately, the two sheets then brought together and superposed one upon the other to cause the incisions to 50 register, and finally they are acted on by a severing die which severs the incised portions from the sheets and unites them along the severed edges.

These operations are effected by the employment of three different dies, two incising dies and one severing die, which dies are arranged one in advance of the other so that the two sheets are acted on separately by the two incising dies respectively and 60 then both sheets in superposed condition are acted on by the severing die.

Referring to Fig. 4, 1^a indicates a bed or support over one end of which is arranged a vertically reciprocating die head 11 pro- 65 vided on its lower face with a sharp in-

cising die 12 of curved form corresponding to the sides and bottom of a dress shield flap as shown in Fig. 5. Arranged alongside of this die head is an elevated bed plate 13 which is supported a slight distance 70 above the bed plate 1^a, by legs 14 so that it is spaced therefrom for the purpose presently to be described. Arranged over the elevated bed is a second vertically reciprocating die head 15 having on its under face 75 a curved die 16 as shown in Fig. 6, similar in form to the die 12. Also arranged over the bed 1^a is a third reciprocating die head 17 having on its under side a severing die 18 which is of a form as shown in Fig. 7, 80 to form the upper edge of the dress shield. The incising die 12 coöperates with the bed 1^a in acting on one sheet 19, and the die 16 coöperates with the elevated bed plate 13 in acting on another sheet 20, while the die 85 18 coöperates with the bed 1^a in acting on the two sheets superposed upon each other. The sheet 19 is unwound from a supply roll 21 rotatably supported at the side of the die head 11, and is allowed to hang loose where 90 it passes onto the bed 1^a, the sheet extending from this point beneath the die head 11, beneath the elevated bed plate 13, and finally beneath the die head 17. The other strip 20 is unwound from a supply roll 22 rotatably 95 supported between the die heads 11 and 15, the material from this spool being likewise allowed to hang loose where it passes onto the elevated bed plate 13, from which point it passes beneath the die head 15, and leaving the elevated bed plate 13, it is superposed on sheet 19 and passes beneath the die head 17. The two sheets are acted on beyond the die head 17 by means of upper and lower feed rolls 7^a and 8^a, which are operated 100 in the manner similar to the operation of the feed rolls 7 and 8 before described, and which coöperate with the supply rolls 21 and 22 in drawing the two sheets along beneath the several dies at the same speed 105 that they are unwound from the supply rolls and free from strain or tension.

In the operation of the mechanism described, the two sheets of material are unwound by the rotation of the supply rolls 115 21 and 22 and are advanced by the feed rolls beneath the several die heads, the sheet 19 between the bed plate 1^a and the die head 11, the sheet 20 between the elevated bed plate 13 and the die head 15, and the 120 two sheets in superposed condition between the bed 1^a, and the die head 17. As the several dies descend, a curved incision will be made in sheet 19 by the die 12 and a like incision will be made in sheet 20 by the 125 die 16, and these operations are repeated until by the advance of the two sheets, the incisions made by the two dies will fall in registry with each other as shown in the upper portion of Fig. 8, as the sheets in super- 130

posed condition are passed beneath the die head 17. The die head 17 in descending will cause its severing die 18 to act on the superposed sheets and will completely sever the incised portions or blanks from the sheets as shown in the lower portion of Fig. 8, while at the same time the edges formed by the die 18 will become united and the two blanks of the shield will be joined together as shown in Fig. 9. These operations are repeated, the material being advanced successively between the successive actions of the dies.

Having thus described my invention, what I claim is:

- 15 1. The method of forming articles from sheet rubber which consists in feeding separate sheets of said material, incising said sheets separately along predetermined lines, superposing said sheets one upon the other to cause the incisions to register, and severing the incised portions from the sheets while causing the material of said portions to unite along the severed edges.
- 20 2. The method of forming articles from sheet rubber which consists in feeding separate sheets of said material, incising said sheets separately along predetermined and similar lines, superposing said sheets one
- 25 upon the other to cause the incised portions
- 30

to register with each other, and severing said incised portions from the strips while causing the material of the incised portions to unite along the severed edges.

3. The method of making dress shields 35 from sheet rubber which consists in feeding separate sheets of said material, incising said sheets separately along lines corresponding to the sides and bottoms of the flaps of the shield, superposing said sheets 40 one upon the other to cause the incisions to register, and severing the flaps from the sheets along the upper edges of the flaps, while causing said upper edges to unite with each other and connect the flaps together. 45

4. The method of making articles from unvulcanized sheet rubber without the application of heat or cement, which consists in incising two superposed sheets of said material to partially separate portions therefrom, and completing the separation of the uncised portions from the sheets by severing the same along lines connecting the ends of the incisions while causing the materials of the separated portions in unheated condition to flow into each other and form an integral joint along the severing lines. 50

In testimony whereof, I have affixed my signature.

RUFUS A. FREEMAN.
